[57] **CLAIM**

The ornamental design for a reading light bar, as shown and described.

DESCRIPTION

FIG. 1 is a perspective view of the reading light bar showing our new design;

FIG. 2 is a left end elevational thereof, the right end elevational view being a mirror image of the view shown in this Figure;

FIG. 3 is a front elevational view thereof;

FIG. 4 is a rear elevational view thereof;

FIG. 5 is a top plan view thereof; and,

FIG. 6 is a bottom plan view thereof.
